MAN-SHAPED HEAD FOR RECREATIONAL EQUIPMENT

Robert S. Wormser, Hillsdale, Mich., assignor to Game-Time, Inc., Litchfield, Mich., a corporation of Michigan

Filed Mar. 20, 1968, Ser. No. 11,072

Term of patent 14 years

U.S. Cl. D34—4

Int. Cl. D21—04

FIG. 1

FIG. 3

FIG. 1 is a front perspective view of a man-shaped head for recreational equipment in accord with my new design, the rear being identical thereto in appearance,

FIG. 2 is a side elevational view, the opposite side being identical thereto, and

FIG. 3 is a top plan view of my new design.

I claim:

The ornamental design for a man-shaped head for recreational equipment, substantially as shown and described.
